CRATE BUILDING MACHINE

Max C. Rutzan and Lloyd W. Pardee, Pontiac,
and Alfred J. Stecker, Orchard Lake, Mich., as-
signors to Steel Bound Container Corporation,
a corporation of Florida

Application October 28, 1931, Serial No. 571,618

5 Claims. (Cl. 1—12)

The invention relates particularly to machines for manufacturing baskets or containers adapted to be used in shipping fruit or the like, and the principal objects thereof are to provide a machine for this purpose which will manufacture such articles, rapidly, efficiently and economically; to provide a machine for manufacturing baskets, containers and the like, which will fabricate such articles in a substantially automatic manner; to provide a machine of the above character by means of which the articles fabricated will be uniform, and the parts comprising such articles, assembled in a secure manner; and to provide a machine which will automatically assemble and secure wooden slats and metal ribbon bands together, without necessitating the use of separate fastening means.

For a complete understanding of the invention reference may be had to the accompanying drawings forming a part of the specification wherein:

Figure 1 is a perspective view of a machine constructed according to one form of the invention:

Fig. 2 is an end view of the machine shown by Fig. 1, taken from the work intake end thereof indicated by the arrow 2, with certain parts shown in cross section, and other parts broken away, for the purpose of clarifying the construction;

Fig. 3 is a cross sectional view taken substantially along line 3—3 of Fig. 2;

Fig. 4 is a cross sectional view on a larger scale, taken substantially along line 4—4 of Fig. 1;

Fig. 5 is a cross sectional view taken substantially along line 5—5 of Fig. 4;

Fig. 6 is a cross-sectional view, on a larger scale, taken substantially along line 6—6 of Fig. 4, illustrating the upper die for forming the projections in the metal band shown by Fig. 22;

Fig. 7 is a cross-sectional view on a larger scale, taken substantially along line 7—7 of Fig. 4, illustrating the lower die for forming the projections shown by Fig. 22;

Fig. 8 is a cross sectional view taken substantially along line 8—8 of Fig. 7;

Fig. 9 is a cross sectional view on a larger scale, taken substantially along line 9—9 of Fig. 1;

Fig. 10 is a cross sectional view taken substantially along line 10—10 of Fig. 9;

Fig. 11 is a cross sectional view taken substantially along line 11—11 of Fig. 10;

Fig. 12 is a side elevational view of the construction shown by Fig. 10, taken in the direction indicated by the arrow 12;

Fig. 20 is a cross sectional view on a larger scale, taken substantially along line 20—20 of Fig. 19;

Fig. 21 is a plan view of a fabricated article which may be manufactured by means of the machine illustrated in the previous figures;

Fig. 22 is a fragmentary, perspective view of one of the metal ribbon bands shown in Fig. 21, illustrating fastening means provided in the band for securing it to wooden slats;

Fig. 23 is a fragmentary perspective view of an end portion of one of the metal ribbon bands shown in the article illustrated in Fig. 21, indicating the manner in which the ends of the band are formed to provide means for securing opposed ends of each band together to provide an annular assembly;

Figure 24 is a detail, cross sectional view illustrating the hopper for the wooden slats, and the manner of removing individual slats therefrom;

Fig. 25 is an enlarged view, in cross section, of the dies used for securing the slats to the bands, as shown by Fig. 13;

Fig. 26 is a view, on a larger scale, taken substantially along line 26—26 of Fig. 14;

Fig. 27 is a cross sectional view taken substantially along line 27—27 of Fig. 26;

Fig. 28 is an enlarged view, in cross section, illustrating the mechanism employed for cutting the metal bands at the discharge end of the machine.

The machine illustrated by the drawings, and which presently will be described, is particularly adapted for manufacturing containers such as that disclosed in the application for patent of H. M. Warren, Ser. No. 546,085, filed June 22, 1931. Also the machine may be utilized for

manufacturing containers such as those disclosed in the application for patents of H. M. Warren, Ser. No. 486,751, filed October 6, 1930, and J. B. Brooks, Ser. No. 466,682, filed July 6, 1930, by 5 making obvious changes in the machine which will be readily appreciated by those skilled in the art.

The article to be manufactured by the machine is illustrated herein particularly by Figs. 21, 22, 10 and 23 and each article as best shown by Fig. 21, comprises a plurality of spaced metal bands 10 interconnected by a number of equally spaced wooden slats 13 extending transversely between the bands. For the purpose of fastening an end 15 of each slat to the band, the latter, during the initial operation of the machine is at intervals formed with spaced pairs of V-shaped projections indicated at 16 and 17 and intermediate the pairs of projections, the band is formed with a semi-cylindrically shaped anchor 18. When a slat is 20 secured to a band, the end of the slat is forced down against the projections 16 and 17, and the anchor 18, which forces the projections through the slat and the extreme pointed portions of such 25 projections through the opposite side thereof. These extreme pointed portions of the projections are then bent over against the slat thereby securely clamping the slat to the band. The anchor 18 during this operation, is not forced entirely through the slat because its depth is not 30 greater than the thickness of the slat. This anchor has a particular purpose as clearly set forth in the later filed application for patent of H. M. Warren. While it is to be understood that the 35 article manufactured by the machine may comprise any number of slats assembled with a plurality of spaced metal bands, preferably each article comprises twelve equally spaced slats.

During the operation of the machine, the metal 40 bands are directed therethrough in continuous form, and the slats are secured thereto in such manner that after each twelfth slat is secured to the band, the bands are moved a greater distance than the usual distance spacing the slats, 45 thereby providing a greater length of band between each group of twelve slats. That portion of each band between each group of twelve slats, then is crimped as indicated at 20 and 21, and the manner in which each crimp is formed is 50 clearly illustrated by Fig. 23. It will be noted that each crimp comprises upwardly pressed arcuate portions 22 and 23 at opposite sides of the band, and an intermediate arcuate portion 24 pressed downwardly. The projections 22, 23, 55 and 24 cooperate to provide an eye for receiving a cotter pin. While the crimps 20 and 21 are formed similarly, the projection 24 in one crimp is slightly larger than the projection 24 in the other, and consequently if the latter should be placed over the other in superimposed relation, the projection 24 in the upper crimp, will project 60 downwardly between the adjacent ends of the portions 22 and 23 in the lower crimp. Hence it will be apparent that opposite ends of the bands in each article manufactured will have complementary crimps and that by bending the article into annular form, opposite ends of each band may be arranged with the crimps disposed in 65 superimposed and complementary relation and that cotter pins may be utilized for securing the ends of the bands together to provide an annular construction. After the crimps 20 and 21 are 70 formed, each band is severed between the crimp

20 and 21, this severing operation constituting the last function of the machine.

The general arrangement of the machine may be understood by referring to Fig. 1. In this figure, the intake end of the machine is at the right, 5 and the first operation of the machine on the metal bands, is to draw such bands into the machine. The letter A indicates the mechanism employed for this purpose, which comprises generally, rollers engaging opposite surfaces of the 10 band for drawing the bands into the machine.

Then the bands are formed with the projections shown by Fig. 22 in that part of the machine indicated by the letter B. Following this operation, the bands pass beneath a hopper C having 15 the wooden slats 13 therein and which are sequentially positioned properly on the bands. Then the slats are secured to the bands by mechanism indicated generally at D. Then the bands and slats pass through mechanism E where the crimps 20 20 and 21 are formed and the bands severed intermediate the crimps.

Referring to Fig. 2, which shows the intake end of the machine, the driving power for the latter is derived from a motor 30, having a gear 31 25 on its shaft which meshes with a second gear 32 keyed to a shaft 33. A gear 34 on the last mentioned shaft meshes with a gear 35 on a main driving shaft 36 extending the entire length of the machine below a table 36'. This shaft, as 30 shown by Fig. 16 is journaled in opposite ends of the machine frame indicated at 37, and adjacent the motor end of the shaft a one way clutch 38 is provided to prevent possible reverse operation of the machine. In view of the fact that the various 35 operations performed by the machine in assembling the slats and the band must be effected when the slats and bands are stationary, means are provided for moving the band and slats through the machine periodically and by small 40 increments. These bands are moved through eleven small increments of movement and then a slightly greater distance for the purpose as previously explained, of providing a larger length of band between each group of twelve slats for 45 the crimps 20 and 21. The means for obtaining this periodic movement of the bands through the machine now will be described.

Referring to Fig. 16, the shaft 36 at one point is 50 provided with a bevel gear 40 which meshes with a bevel gear 41 secured on a transversely extending shaft 42 and the latter in turn is provided with a pinion 43 on its opposite end which meshes with a pinion 44 mounted on a shaft 45 disposed adjacent and parallel to the shaft 42. Referring 55 to Figs. 17, 18, and 19, in conjunction with Fig. 16, the shaft 45 is provided with a wheel 46 having a series of equally and rather widely spaced teeth 47 on its periphery which are adapted to engage circumferentially spaced pins 48 mounted on a disc 49 secured to a shaft 50. Twelve pins are provided on the disc which are equally spaced with the exception of two pins 51 and 52, spaced a greater distance. From this description it is apparent that the teeth 47 on wheel 46, will move the disc through periodic small increments of rotary movement, and, as one of the teeth 47 engages one of the pins 48 it will move the disc until the tooth disengages the pin, and then the disc will remain stationary until the next tooth 47 engages the next pin on the disc. The stationary periods of the disc will be substantially equal as far as time is concerned but when one of the teeth 47 engages the pin 52, it will move 60 65 70 75 80 85 90 95 98

the disc through a greater increment of rotary movement because this pin will be so positioned that the tooth 47 will engage it sooner than the teeth 57 will engage the other pins.

- 5 An annular ring 55 is secured to the disc 49 at the outer periphery of the latter, by means of machine bolts 53 extending through elongated slots 54 in the disc. Consequently, the ring may be adjusted circumferentially with respect to the 10 disc. This ring is provided with twelve teeth 56 on its periphery and two of such teeth 57 and 58 are spaced a greater distance than the usual space between the teeth. It should be noted that the tooth 57 is somewhat longer than the other 15 teeth on the ring. The teeth 57 and 58 are located on that side of shaft 50 generally opposite the pins 51 and 52 on the disc and consequently when the pins last mentioned are in a position of proximity to the wheel 46 and the teeth 47 thereon, the teeth 57 and 58 will be located at 20 the right upper side of the ring 55 in a position approaching a vertical plane coinciding with the axis of the shaft 50.

As best shown by Fig. 16, the shaft 50 is provided with a second wheel indicated at 59, which is constructed identically to the assembly comprising the disc 49 and ring 55, but such wheel 59 is not provided with pins as indicated at 48 on disc 49. The teeth on the wheel 59 have positions corresponding to the teeth on ring 55 and it is apparent that by means of the adjustable securing means between the disc and the annular ring, the teeth on the two wheels may be adjusted with respect to the shaft 50 and consequently the 35 pins 48.

The wheels 55 and 59 project slightly above the table 36, through openings therein, as shown by Figs. 9 and 10 and the teeth on the wheels are adapted respectively to engage rear edges of the 40 slats 13 after the slats are secured to the bands 10 and push the assembly of slats and bands through towards the discharge end of the machine. As will be more clearly set forth herein-after, after a slat is secured to the bands, one 45 of the teeth 56 on each of the wheels 55 and 59 engages the rear edge of such slat and moves the slat and band assembly through the machine a predetermined distance. Then the wheels remain stationary until the succeeding tooth 47 on 50 wheel 46 engages the next pin on the disc 49. During this stationary period the next slat is moved into proper position on the band and secured thereto and then the next teeth on the wheels 55 and 59 engage the rear edge of this 55 slat and again move the slat and band assembly through the machine the same distance as mentioned previously. However, when the teeth 57 are in a position to engage the rear edge of a slat one of the teeth 47 on wheel 46 will engage 60 pin 52 on the disc and move such disc and the wheels 55 and 59 through a greater increment of rotary movement and consequently the teeth 57 will move the slat it engages, a greater distance through the machine. It is apparent that the 65 teeth 57, being longer than the other teeth, will remain in engagement with such slat for a greater amount of rotary movement of the wheels 55 and 59 in order to effect this greater movement of the slat and band assembly.

70 To prevent overrunning of the wheels 55 and 59 following disengagement of one of the teeth 47 with one of the pins 48, a cam disc 60 (Figs. 18, 19, and 20), is mounted on a shaft 61 having a pinion 62 which meshes with the pinion 44 75 on a shaft 45. The disc 60 is provided with a

cam groove 63 which as best shown by Fig. 20, constitutes a guide for a cam follower 64, secured to a block 65 slidably mounted in a guideway 66 formed in a casing 67 in which the shaft 61 is journaled. The arm 65 is provided with an offset portion 68 having a surface 69 which as best shown by Fig. 19 is adapted to engage the lower side of one of the pins 48 immediately after one of the teeth 47 on wheel 46 is disengaged from such pin. The surface 69 therefore prevents further rotary movement of the pin which it engages, but when the succeeding tooth 47 on wheel 46 is about to engage the next pin 48 on disc 49, the cam roller 64 is so positioned in the cam groove 63, that the arm 65 begins to move downwardly and the offset portion 68 thereof out of the path of movement of the pins, thereby permitting movement of the disc. After the tooth 47 engages the pin on disc 49 and moves the disc the desired amount, the cam roller 64 again operates with the cam groove 63 in such manner that the arm 65 is moved upwardly and the cam surface 69 again engages the lower side of the pin immediately after such pin has been disengaged from the tooth on wheel 46. In this manner the disc is moved the desired amount each time and the pins are always properly positioned for engagement by the teeth 47.

Referring again to Fig. 16, the shaft 50 is also provided with a bevel gear 71 which meshes with a bevel gear 72 mounted on a shaft 63 which extends to the front end of the frame 37. At its forward end, shaft 73 is provided with a bevel gear 74 which meshes with a bevel gear 75 on a vertically disposed shaft 76.

Now referring to Figs. 2 and 3, relating to part A of the machine, the shaft 76 projects upwardly through and is journaled in the table 36 of the machine, and is provided with a bevel gear 78 which meshes with a bevel gear 79 mounted on 40 a shaft 80 extending transversely above the table. At equally spaced points, the shaft 80 is provided with rollers 81 having knurled peripheries for engaging the under surfaces of three metal ribbon bands 10, although it is apparent that the machine may be so operated that only two bands are fed therethrough engaging two of the rollers. Each of the metal ribbon bands is directed through guideways 84 located forwardly and rearwardly of the rollers, in alignment therewith, and as each band is directed through a guideway and over one of the knurled rollers, it is adapted to be clamped down against the knurled rollers by other rollers 85. The latter are journaled in the lower bifurcated ends of 50 arms 88, 89 and 90 respectively, depending from a cross head 91 vertically slidable in guideways 92 and 93 formed in adjacent sides of portions 94 and 95 of the framework 37 of the machine, projecting above the table 36.

Each of the arms 88, 89 and 90 has a shank 96 which is slidably mounted in a socket 97 formed in the cross head 91, and a spring 98 located in a socket 99 in the end of the shank 96, and engaging the base of such socket and an adjustable screw device 100 secured to the cross head, resiliently connects the arms to the latter. The cross head 91 is adapted to be reciprocated by means of a shaft 101 having cams 102 and 103 adapted to engage a plate 104 (Fig. 3) forming a 70 part of the cross head 91. Outwardly of the frame member 95, the shaft 102 is provided with a handle 105. When the handle 105 is rotated, it is apparent that the cams 102 and 103 will move the cross head downwardly, and hence the rollers 85 75

will be resiliently pressed against the metal ribbon band directed over the knurled rollers 81. The metal ribbon bands are fed into the machine from reels of such material and it is apparent that the knurled rollers 81, will positively draw the bands into the machine. Likewise it is apparent that the bands will be fed into the machine periodically and through small increments of length, in such manner that the bands will be moved eleven equal increments of length through the machine and then through a twelfth increment of greater length. All of this should be clear in view of the driving connection between shaft 80 on which the knurled rollers are mounted, and shafts 76, 73, drivingly connected to shaft 50 which is periodically driven in the manner previously described in connection particularly with Figs. 16, 17, 18, and 19.

As the metal ribbon bands, either two or three in number depending on the width of the article to be manufactured, are directed through the machine, the first operation that is performed on them is the formation of the V-shaped projections 16 and 17, and the anchor projection 18 shown more particularly by Fig. 22. The mechanism B for performing this operation now will be described.

Referring to Figs. 4 and 16, it will be noted that shaft 36 is provided with a bevel gear 115 which meshes with a bevel gear 116 secured on a transversely extending shaft 117 located below the table 36'. This shaft is provided with three eccentrics 118, 119 and 120 having arms 121, 122 and 123 respectively, slidably projecting in an upward direction through openings in the table. As best shown by Fig. 5, each of the arms is pivotally connected as indicated at 124 to a die head 125, which as shown by Fig. 4 is provided with guide pins 126 and 127 projecting downwardly into openings in the table 36' for the purpose of guiding the reciprocatory movement of the die head in a vertical manner. Other eccentrics 128 and 129 mounted on the shaft 117 are provided with arms 130 and 131 that are pivotally connected at their upper ends to rods 132 and 133 slidably projecting through openings in the table 36'. The upper ends of rods 132 and 133 are adjustably secured by means of screw devices 134 to a cross head 135 extending transversely of the table. The cross head 135 is guided in its vertical reciprocatory movement by means of pins 136 and 137 projecting downwardly from a cross member 138 on a yoke 139 secured to opposite sides to the table 36'. These pins are secured to the yoke 139 and slidably project into openings 140 formed in the cross head. The cross head 135 is provided with upper dies 141 which are disposed in vertical alignment with the lower dies 125. The eccentrics 118, 119 and 120, and the eccentrics 128 and 129 are so arranged on shaft 117 that the dies 125 and 141 on the groups of eccentrics respectively, are always moved in opposite directions, and hence the dies are first brought together and then are moved apart.

The bottom die 125 as best shown by Figs. 7 and 8, comprises a base 145 having a die element 146 composed of relatively hard metal, which is secured thereto and in a groove in the base, by means of screws 149. The die element is provided with a pair of spaced, inverted V shape projections 147 and 148 and a pin 149 located centrally between such projections, which has a semi-spherical upper end. These parts of the die elements are adapted to cooperate with the upper

die for forming the projections 16, 17 and 18 in the metal bands as indicated in Fig. 22. The die element 146 also includes a block 150 at that side thereof opposite the projections 147 and 148 as shown by Fig. 7, for preventing side movement of the upper die, and also a dowel pin 151 which connects the die element to the base 145 for assisting in properly locating the element.

The upper die 141 has a base 155 provided with a die element 156 secured thereto by screws 157. The die element 156 has apertures in one end thereof 158, 159 and 160, complementary respectively to the V-shaped projections 147 and 148, and the semi-spherical head 149 on the lower die element, and cooperate therewith to form the projections 16, 17, and 18 in the band as shown by Fig. 17. It will be noted that these projections and openings are so formed in the die elements, that the V-shape projections 16 and 17 shown in the band in Fig. 19 are gradually sheared along the V shape edges of projections 147 and 148 in the lower die element, and then after the shearing operation they are bent into vertical position by continued movement of the upper die element slightly below the V shape projections in the lower die element. As is true of the lower die element, a dowel pin 160 also connects the upper die element 156 to the die base 155 for properly locating the element. The dies 126 and 141 are guided by each other in their reciprocatory movement, by means of rods 161 and 162 slidably projecting into openings in the upper die base 155, and which are secured to the lower die base 145.

As best shown by Fig. 5, each of the metal bands 10 is guided between the upper and lower die elements in the mechanism shown by Fig. 4, by means of a device 164 at the entrance and discharge sides of the mechanism. It is apparent that the guiding device 164 can have a rectangular opening for receiving the band end, since the band has no projections at this side of the construction, but when the band has passed between the dies, and is provided with projections, it is necessary to have the guiding device provided with a suitable groove in order that the projections may pass therethrough. If the band should tend to stick to the lower die element, any suitable and resilient stripping devices may be provided on the element for moving the band away from the projections 147 and 148 on the element after the projection forming operation. To prevent the band from sticking to the upper die element when the latter begins to move upwardly, resilient stripping devices 166 indicated in Fig. 6, may be provided, which comprise resiliently mounted pins adapted to project below the surface of the upper die element and force the band downwardly when the upper die element begins to move upwardly after the projection forming operation.

Referring to Figs. 1, 9, and 24, it will be noted that the hopper C is inclined slightly to be vertical, and that it is adapted to contain a number of wooden slats 13 disposed in stacked relation. The lowermost slat rests on a plurality of supporting bars 170 shown by Figs. 9 and 10, and the slats are removed from the hopper and moved along such bars in sequential relation. For removing the slats and moving them along in a periodic manner corresponding to the periodic movement of the bands in the machine, mechanism is provided which is driven by shaft 117 shown by Fig. 5. In the latter figure it will be noted that the shaft 117 is provided with a crank 75

arm 173 which is pivotally connected to a link 174. Now as best shown by Figs. 9, 12, and 16, it will be noted that the rear end of link 174 is pivotally connected as indicated at 175 to the free 5 end of an arm 176 secured to a shaft 177 extending transversely of the machine below the table 36' and the hopper C. This shaft, as best shown by Fig. 9, is provided with three crank arms 178, 179 and 180 which are spaced longitudinally of 10 the shaft. As best shown by Figs. 9 and 12, each of the crank arms is pivotally connected at its free end to a link 181 and the link in turn is pivotally connected to a block 182 which is slidably mounted in a guideway 183 formed between 15 upstanding bracket members 184 and 185 on the table 36', the latter of which supports one of the bars 170 upon which the wooden slat is supported. Each of the sliding blocks 182 has a lip portion 186 shown best by Fig. 24, projecting 20 slightly above the slat supporting bar 170 adjacent thereto, and consequently is adapted to engage one edge of the slat and move it along over the bar. Now referring to Fig. 24, the hopper C adjacent the discharge side of the machine, 25 is provided with an offset, housing portion 187 which contains a number of spring pressed balls 188, each of which seats in a frusto-spherical opening 189 provided below the ball. This arrangement causes the lower portion of the ball 30 to project to a point adjacent the upper surface of the bar 170 and normally in front of the lowermost slat 13. When the sliding block 182 is moved forwardly, the lip 186 moves the lowermost slat against the balls, causing the balls to 35 move upwardly against the action of the springs thereby permitting the slat to be moved below the ball. The balls are so positioned, however, that the movement of the lowermost slat will not cause the next slat thereabove to be moved along 40 therewith, because this next slat engages a more nearly central part of the balls during the movement of the lowermost slat. As soon as the lowermost slat is moved past the ball, the next slat immediately drops downward. It should be 45 understood, however, that the block 182 is of sufficient length, that in its movement forwardly it does not move beyond the stack of slats, and hence it in fact supports the next slat until the block is reversed in its movement and brought 50 back to its initial position, following which the slat falls below the lip 186 and upon the bar 170 into a position in which it will be engaged by the block 182 when the latter again moves forwardly.

55 The slat removed from the hopper by the blocks 182 during their forward movement, is moved upon supporting blocks 190 shown by Fig. 10, with the forward edge of the slat engaging spring pressed latch members 193, shown both by 60 Figs. 10 and 11. This latch properly positions the slat with respect to the dies adapted to secure the slat to the bands.

As shown by Figs. 13 and 25, each slat 13 when it is disposed on the plate 193, is held slightly 65 above such plate by means of slidable blocks 196 disposed in vertical apertures 197 in the plate and normally pressed upwardly by means of springs 198. These blocks are so arranged, that the slat is spaced slightly above the projections 70 16 and 17 on the metal bands which rest directly on the upper surfaces of plates 193. In this connection it is to be observed that the upper surfaces of bars 170 shown by Fig. 9 upon which the slats are moved to the plates 193, are in substantially 75 the same plane as the upper surfaces

of the spring pressed blocks 196, this arrangement permitting the movement of the slat to its position upon the spring pressed blocks 196 without interference by the projections 16 and 17 on the band. 5

For forcing the slat downwardly against the points of projections 16 and 17 on the bands, the mechanism D is provided, which includes a vertical shaft 200 shown by Fig. 9, which has a bevel gear 201 on its lower end meshing with a bevel gear 202 on the main driving shaft 36. At its upper end shaft 200 is provided with a bevel gear 203 which meshes with a bevel gear 204 on a shaft 205 journaled in a frame work 206 fastened to the table 36'. Shaft 205 is provided with two eccentrics 207 and 208 connected to connecting rods 209 and 210 depending therefrom, and the lower ends of the connecting rods are pivotally connected to a crosshead 211 (Figs. 12 and 13) mounted for vertical sliding movement in the frame work 206. 10 15 20

Again referring to Figs. 13 and 25, the crosshead 211 is provided with die elements 212, each of which has a flat lower surface 213 and a spring pressed block 214 normally projecting below the 25 surface 213. When the crosshead moves downwardly, the block 214 initially engages the upper surface of the slat and moves it and the blocks 196 on the plate 193, downwardly thereby forcing the slat downwardly against the projections 16, 30 17 and 18 on the metal band until the extreme pointed portions of the projections 16 and 17 are exposed above the upper surface of the slat. Further movement thereof is prevented by engagement of the slat with the bands, and then the 35 block 214 is forced upwardly into its recess in the die 212 and the surface 213 engages the slat and bends the extreme pointed portions of the projections 16 and 17 over to clamp the slat securely to the band. When this operation has been performed, the eccentrics 207 and 208 so operate 40 that the crosshead 211 is moved upwardly. 45 50 55 60 65 70 75

During the time that this operation is being performed on the slat and bands, the slat is located between two of the teeth on wheels 55 45 and 59, Figs. 10 and 12, and such wheels are stationary. Immediately after the slat is secured to the bands and the crosshead 211 begins to move upwardly, the wheels 55 and 59 turn through one of their increments of movement as previously explained, causing the rear teeth on such wheels to engage the rear edge of the slat and move it and the band through one increment of movement toward the discharge end of the machine. It is apparent that the 55 spring pressed latch 193 will not prevent such movement of the slat since it will move downwardly and out of the path of movement of the slat upon pressure being exerted against the rear edge of the slat by the teeth on the wheels 60 55 and 59, but as soon as the slat has moved past the latch 193, the latter will be reverted to its normal position for engagement with the next slat. 65 70 75

Now referring to Figs. 14, 15, 26, 27, and 28, and particularly to that part E of the machine, a frame 215 is supported by the table 36' and, as best shown by Fig. 15, has a pair of transversely extending shafts 216 and 217 journaled 70 in the upper part thereof. The shaft 216 is provided with a pair of eccentrics 218 and 219 which are operatively connected to connecting rods 220 and 221 which in turn are pivotally connected to a crosshead 222 mounted for verti- 75

cal sliding movement in the frame work. The crosshead is provided with three dies, 223, 224 and 225 adapted to co-operate with stationary dies 226, 227 and 228 on the table. As best shown by Figs. 15, 26, and 27, each of the dies on the crosshead 222 is provided with a die element 230 which has portions 231 and 232 adapted respectively to form the crimps 20 and 21 in the metal band. As best shown by Fig. 27, each of the portions 231 and 232, this figure illustrating the portion 232, has depressions 233 and 234 and an intermediate projection 235 of a semi-cylindrical shape adapted to form the central portion of the crimp. The lower die includes a die element 236 complementary to the upper die element 230 and in conjunction therewith forms the crimps 20 and 21 in the metal band. As previously explained, these crimps are not exactly the same size but to the contrary when one is disposed on the other, in superimposed relation, they form an eye for receiving a cotter pin. When the crimps are formed in the band the latter is pushed upwardly away from the lower die element when the crosshead is moved upwardly, by means of a spring pressed pin 237 which not only separates the band from the lower die but facilitates further movement of the band through the machine. Movement of the dies is accurately controlled by means of pins 238 and 239 shown by Fig. 27, which are secured in the upper die and slidably project into openings in the lower die. In view of the fact that the crimps are formed only in the band between groups of twelve slats respectively, the mechanism performing such crimps can operate only at infrequent intervals and the mechanism for securing this result will now be described.

Referring to Fig. 14, the shaft 36 is provided with a bevel gear 240 which meshes with a bevel gear 241 secured to a shaft 242 projecting upwardly through the table 36'. This shaft is provided with a clutch element 243 which is adapted to engage a complementary clutch element 244 mounted on a shaft 245 projecting upwardly into the frame work 215. At its upper end shaft 245 is provided with a bevel gear 246 which meshes with a bevel gear 247 on shaft 216. The lower clutch element 243 is splined to shaft 242, and is adapted to be moved upwardly into engagement with clutch element 244 by means of a bell crank lever 248 pivoted intermediate its ends as indicated at 249 on a stationary part of the frame work, and which has a portion 250 operatively connected to the clutch element 243. The upper end of the bell crank 248 has a roller 251 journaled thereon, adapted to engage a cam 252 on shaft 245, which so cooperates with the roller 251 when the clutch elements are engaged and the shaft 245 begins to rotate, that the clutch elements will remain engaged for a predetermined time necessary to reciprocate the crosshead 222 once, and then the roller will move into a recess in the cam and not only limit further movement of the shaft, but allow disengagement of the clutch elements. The lower end of the bell crank is provided with a pin 253 which is adjustably mounted and this pin is adapted to engage a pin 254 mounted on a disc 255 which is rigidly secured on a shaft 256. A spring 257 connected to the bell crank and to a stationary part of the frame work normally maintains the bell crank in its inoperative position and the clutch elements disengaged, with the pin 253 in the path of movement of the pin 254 on the disc.

Shaft 256 is driven by means of a relatively large gear 260 as best shown by Fig. 16, meshing with a pinion on a countershaft 262 that in turn is provided with a pinion 263 which meshes with a pinion 264 on shaft 36. This arrangement in fact constitutes a reduction gearing and causes the shaft 266 to rotate rather slowly. The arrangement of the mechanism is such that after each group of twelve slats has passed between the upper and lower dies in the crimp forming mechanism, the pin 254 on disc 255 as shown by Fig. 14, engages the pin 253 on the bell crank 248 and causes this arm to so turn that the clutch element 243 is moved upwardly into engagement with the clutch element 244 thereby drivingly connecting the shaft 36 with shaft 245 and hence shaft 216 which causes the die elements to be brought together for forming the crimps in the band.

After the crimps are so formed in the bands, the latter and slats continue to move through the machine until the crimped portions of the bands are disposed between upper and lower die elements 270 and 271 of the cutting off mechanism shown by Fig. 15. The upper cutting die elements are secured to a vertically slidable crosshead 272 which is mounted pivotally on connecting rods 273 operatively connected to eccentrics 274 mounted on shaft 217. Shaft 217 is connected to shaft 36 in the same manner that shaft 216 is connected thereto, and the clutch elements in such connection are controlled by a bell crank 275 shown by Fig. 15. This bell crank is adapted to be operated by a pin 276 on a disc 277 mounted on shaft 256. However, as best shown by Fig. 14, pin 276 on disc 277, is displaced circumferentially with respect to pin 254 on disc 255 and, consequently, the clutch element on the vertical shaft, operating shaft 217 will not be brought into engagement until a short time after operation of the clutch elements connecting shafts 242 and 245. Following disengagement of the pin 254 with pin 253 controlling the crimp forming operation, the crimp portion of the band is moved into a position between the cutting dies 270 and 271, and then the pin 276 on disc 277 operates the bell crank 275 to connect the shaft 217 with shaft 36 thereby causing the upper cutting die 270 to be moved downwardly against the lower cutting die.

The bands are cut intermediate the two crimps by means of a lower cutting element 280 on the lower die as shown by Fig. 28, and an upper shearing element 281 on the upper die. Prior to the cutting operation the bands are supported on spring pressed blocks 282 but upon movement of the upper die downwardly the cutting element 281 moves the block 282 downwardly and the band past the lower cutting or shearing element 280 thereby severing the bands. The upper cutting element has a groove or recess 283 adapted to receive the rearward crimp and prevent deformation thereof during the cutting operation.

It should be apparent from the foregoing description, that the metal bands are directed through the machine by periodic increments of movement and that the initial operation performed on such band comprises forming the projections 16, 17 and 18. When the first slat is secured to the bands by means of such projections, the wheels 55 and 56 engaging the rear edge of each slat after such operation, push the slat toward the discharge end of the machine and consequently the bands associated therewith. In

this connection it is desired to call attention to the fact that the distance between the mechanism for securing the slats to the bands and the mechanism for forming the projections 16, 17 and 18, 5 is substantially equal to the length of one of the articles manufactured, namely, the plurality of bands having twelve slats secured thereto, in order that the larger increment of movement of the bands by the wheels 55 and 59 disposed directly 10 below the mechanism for securing the slats to the band, will simultaneously cause a larger increment of movement of the bands in the projection forming mechanism from which it follows that the projections will be spaced a larger distance 15 at the proper time. The toothed wheels 55 and 59 constitute the means for moving the slat and band assembly through the crimping and cutting parts of the machine and as the teeth on such wheels engage the rear edges of the slats respectively, the slat and band assembly between the 20 wheels and the discharge end of the machine are pushed through the crimping and cutting mechanism. While there is a tendency for the slat and band assembly to bend upwardly out of 25 the horizontal plane when the teeth push the assembly through the machine in this manner, this is prevented by guideways at opposite sides of the machine which maintain the bands in substantially horizontal planes during their movement. 30

For the purpose of facilitating initial operation of the machine, making adjustments, and so forth, means are provided for manually operating the machine as shown by Fig. 16. This means 35 comprises a shaft 290 having a pinion 291 which meshes with a pinion 292 on shaft 117. Shaft 290 also is provided with a pinion 293 which is adapted to be drivingly engaged with shaft 290 by means of a pin 294 on the latter adapted to 40 cooperate with a slot 295 in a boss on one side of the gear. It is apparent that when the pinion 293 is moved in one direction the pin is moved out of the slot 294, thereby disengaging the pinion from the shaft. Movement of the gear in this 45 manner is accomplished by means of a rod 295 operatively connected to the gear and extending through one wall of the frame 37 of the machine. Another pinion 296 meshing with pinion 293 is mounted on a manually operated shaft 297 ex- 50 tending through the frame work and having a handle 298 on its exterior end. When the rod 295 is so moved that the pinion 293 is drivingly connected to shaft 290, rotation of the handle 298 serves to drive shaft 117 through the bevel 55 gears 115 and 116, to the main drive shaft 36, this operation being readily permitted by the clutch 38 without requiring rotation of the motor.

Although only one form of the invention has been described and illustrated in detail, it will be 60 apparent to those skilled in the art that various modifications may be made without departing from the scope of the appended claims.

We claim:

1. A machine for manufacturing box blanks 65 from slats and bands, comprising a forming station; means at said forming station for forming fastening projections in said bands; a securing station; a hopper for slats; periodically operable means for extracting slats from said hopper and 70 delivering said slats to said securing station;

means at said securing station for securing said slats and bands together by means of said fastening projections; and intermittently operable moving means for engaging the secured slats to thereby move said bands and slats forwardly through 5 said machine.

2. A machine for forming box blanks from slats and bands comprising in combination, a forming station; means operable at said forming station for forming fastening projections in said bands; 10 a securing station; a hopper for slats; periodically operable means for extracting slats from said hopper and for delivering said extracted slats to said bands at said securing stations; means at said securing station operable to secure 15 said slats and bands together by means of said projections; and periodically operable means for engaging a secured slat and moving said slat and bands forwardly through the machine in step by step manner, said moving means being effective 20 to cause a greater amount of movement of said slat and bands in certain of said steps than in others of said steps, to thereby increase the spacing between slats at the ends of said blanks. 25

3. A machine for forming box blanks from slats and bands comprising in combination, a forming station; means at said forming station for forming fastening tongues in said bands; a securing station; a hopper for slats; means operable at successive regular intervals to extract slats from said hopper and deliver said slats to said bands at said securing station; means operable at said securing station for securing said slats and bands together by means of said tongues; and intermittently operable moving means for engaging a 30 secured slat to advance said slat and said bands forwardly through the machine in step by step manner, said moving means including a rotary step by step wheel having spaced projections, certain of said projections being spaced apart one 35 predetermined distance and others of said projections being spaced apart a greater predetermined distance. 40

4. A blank forming machine for securing a plurality of slats to a band at successive points 45 therealong, comprising in combination, a securing station, periodically operable means for delivering a slat to said securing station, means for securing said slat to said band at said station, and additional periodically operable means 50 adapted to engage said secured slat to move said slat and said band forwardly through said machine and advance another point of said band to said securing station. 55

5. A blank forming machine for securing a plurality of blanks to a band at predetermined spaced points along said band, comprising in combination a securing station, means at said station for securing said slats to said band, a hopper for slats, periodically operable means for 60 delivering individual slats from said hopper to said securing station, and additional periodically operable means for engaging a secured slat and moving said slats and band forwardly through the machine to bring another of said spaced 65 points to said securing station.
